SKATE

George D. Carter, 5628 E. Lancaster, Apt. 29,
Fort Worth, Tex. 76112

Filed Oct. 22, 1965, Ser. No. 87,740

Term of patent 14 years

(Cl. D34—14)

The top of the skate is plain and unornamented.

The dominant features of my design reside in the portions shown in full lines on the drawings.

I claim:

The ornamental design for a skate, as shown and described.
